Charles W. Englert

BY Partin & Boe ATTY'S.

UNITED STATES PATENT OFFICE.

CHARLES W. ENGLERT, OF PATERSON, NEW JERSEY, ASSIGNOR OF ONE-HALF TO AUGUST J. ENGLERT, OF BROOKLYN, NEW YORK.

WINDOW-CHAIR.

SPECIFICATION forming part of Letters Patent No. 594,612, dated November 30, 1897.

Application filed July 27, 1897. Serial No. 646,110. (No model.)

To all whom it may concern:

Be it known that I, CHARLES W. ENGLERT, a citizen of the United States, residing in Paterson, county of Passaic, and State of New Jersey, have invented certain new and useful Improvements in Window-Chairs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my present invention is to provide a portable bench or seat which can be quickly and firmly secured to window-frames of various size and sills of different widths, of simple, strong, and durable construction, and useful as a support for flower-pots, for persons cleaning the outside of the windows, &c.

The invention consists in the improved portable bench or seat for window-frames, and in the combination and arrangements of the various parts thereof, substantially as will be hereinafter more fully described, and finally embodied in the clauses of the claim.

In the accompanying drawings, in which like letters of reference indicate corresponding parts in each of the several views, Figure 1 is a top plan view of a window-sill and of the adjoining portions of the frame, the latter shown in section, illustrating my improved portable bench or seat in operative position; Fig. 2, an enlarged sectional view on the line xx of Fig. 1; Fig. 3, a detail view showing a certain toothed bar and its locking mechanism, and Fig. 4 a detail view illustrating a modified form of the locking or binding means arranged on the free end of the toothed bar.

In said drawings, a represents the window-frame, b and c the inner and outer sill, d the parting rail, and a' the outer stop-bead, all of usual and well-known construction.

The portable bench or seat consists of a board or frame-plate f , provided at its upper portion with a suitable railing g and on its under side with grooved guide-plates i , arranged centrally on said board and extending longitudinally from end to end thereof. Within said grooved guide-plates are slid-

with flanges i^2 , engaging the grooves in said guide-plates, as clearly shown. Each of the toothed bars i' is controlled by a pawl i^3 , pivotally secured, as at i^0 , to lugs projecting from the end of the board f and provided with a knob i^5 for conveniently lifting said pawl out of engagement with the teeth of said bar i' . On the rounded outer portion i^4 of each toothed bar is loosely arranged a sleeve or collar m , carrying a screw m' , engaged by an internally-threaded sleeve m^2 , adapted to bear against the outer side of the inner sill b and provided with a polygonal-shaped head or enlargement for conveniently operating the same. On the free end of each toothed bar i' is secured a rectangular-shaped block n , adapted to engage the groove (for the outer sash) formed by the parting-rail d and the outer stop-bead a' . A pawl n' is pivotally secured, as at n^0 , to projecting lugs of said block n , and is adapted to bind with its free end against the inner side of the outer stop-bead a' , as clearly illustrated in Figs. 1 and 2.

On the under outer portion of the board f and near each end thereof are arranged guide-plates h at right angles to the guide-plates i and separated from the board by collars h^0 , surrounding the nails or screws by which said plates h are secured to the said board. A flat bar h' is supported by said guide-plates h and is capable of being moved to and from the center line of the board f for a purpose hereinafter stated. At or near each end of said flat bar h' and depending therefrom is arranged a screw h^2 , carrying an internally-threaded sleeve h^3 , adapted to bear on the top portion of the outer sill c to thus retain the board f in a substantially horizontal position. For conveniently operating said sleeve it is provided with a polygonal-shaped head or enlargement as of usual construction. Instead of the squared block n and its binding-pawl n' a mechanism can be used which is illustrated in Fig. 4 of the drawings. In that construction the toothed bar is provided at its outer end with a screw i^6 , on which is arranged the internally-threaded cap i^7 , provided with a pointed end i^8 , adapted to engage the frame a and having a polygonal-shaped head or enlargement for conveniently operating said cap.

When the portable bench or seat is to be secured to the window-frame, the toothed bars i^1 are moved outward until the squared blocks n (carried by said bars) engage and bear against the frame a . Their respective pawls i^3 will hold said bars in extended position, as will be manifest. The sleeves h^3 and m^2 are then operated until they firmly bind upon the top portion of the outer sill c and the outer portion of the inner sill b , respectively. The pawls n' , bearing against the inner side of the outer stop-bead a' , prevent a tilting of the bench, and the latter is thus rendered capable of supporting a considerable weight, as will be manifest.

When the bench is to be removed, the sleeves m^2 are operated in the opposite direction, and after the pawls i^3 have been raised the toothed bars i^1 are slid back, so as to disengage the squared blocks n from the window-frame.

Having thus described my invention, what I claim as new, and desire to secure by Letters Patent, is—

25 1. A portable bench or seat for window-frames, comprising a frame-plate, a guide on the under side of said frame-plate and longitudinally extending from end to end, a pawl-controlled toothed bar slidably arranged in said guide and at each end of the frame-plate, means arranged on the outer end of each toothed bar for locking the same against the sides of a window-frame, a screw carried by each toothed bar and at right angles thereto, 30 an internally-threaded sleeve on each screw and adapted to bear against the outer portion of the inner sill of the window-frame, and means carried by the outer under portion of the frame-plate, for supporting said frame-plate on the top portion of the outer sill, substantially as described.

2. A portable bench or seat for window-frames, comprising a frame-plate, a guide on the under side of said frame-plate and longitudinally extending from end to end, a pawl-controlled toothed bar slidably arranged in said guide and at each end of the frame-plate, means arranged on the outer end of each toothed bar for locking the same against the sides of a window-frame, a screw carried by each toothed bar and at right angles thereto, 45 an internally-threaded sleeve on each screw

and adapted to bear against the outer portion of the inner sill of the window-frame, a series of screws adjustably arranged on the under outer side of the frame-plate and depending therefrom, an internally-threaded sleeve on each of said screws and adapted to bear against the top portion of the outer sill, substantially as described.

3. A portable bench or seat for window-frames, comprising a frame-plate, a guide on the under side of said frame-plate and longitudinally extending from end to end, a pawl-controlled toothed bar slidably arranged in said guide and at each end of the frame-plate, means arranged on the outer end of each toothed bar for locking the same against the sides of a window-frame, a screw carried by each toothed bar and at right angles thereto, 55 an internally-threaded sleeve on each screw and adapted to bear against the outer portion of the inner sill of the window-frame, a series of guide-plates on the under outer portion of the frame-plate and at right angles to the toothed bars, a bar slidably supported by said guide-plates, a screw at or near each end of said bar and depending therefrom, and an internally-threaded sleeve on each of said screws, substantially as and for the purposes described.

4. A portable bench or seat for window-frames, comprising a frame-plate, a guide on the under side of said frame-plate and longitudinally extending from end to end, a pawl-controlled toothed bar slidably arranged in said guide and at each end of the frame-plate, 60 a block on the free end of each toothed bar, a pawl pivotally arranged on each block, a screw carried by each toothed bar and loosely arranged thereon and at right angles thereto, an internally-threaded sleeve on each of said screws, and adjustable supporting means on the under outer portion of the frame-plate and depending therefrom, all said parts, substantially as and for the purposes described.

In testimony that I claim the foregoing I have hereunto set my hand this 21st day of July, 1897.

CHARLES W. ENGLERT.
